CLAIM

We claim the ornamental design for an adhesive bandage with decorated pad, as shown and described.

DESCRIPTION

FIG. 1 is a plan view of a first embodiment of an adhesive bandage with a decorated absorbent pad showing my new design;

FIG. 2 is a side elevational view thereof, the opposite side elevational view being a mirror image thereof;

FIG. 3 is an end elevational view thereof, the opposite end elevational view being a mirror image thereof;

FIG. 4 is a back plan view thereof showing the decorative pattern as seen from the back side of the bandage;

FIG. 5 is a plan view of a second embodiment of an adhesive bandage with a decorated absorbent pad showing my new design;

FIG. 6 is a side elevational view of the embodiment of FIG. 5, the opposite side elevational view being a mirror image thereof;

FIG. 7 is an end elevational view of the embodiment of FIG. 5, the opposite end elevational view being a mirror image thereof;

FIG. 8 is a back plan view of the embodiment of FIG. 5, showing the decorative pattern as seen from the back side of the bandage;

FIG. 9 is a plan view of a third embodiment of an adhesive bandage with a decorated absorbent pad showing my new design;

FIG. 10 is a side elevational view of the embodiment of FIG. 9, the opposite side elevational view being a mirror image thereof;

FIG. 11 is an end elevational view of the embodiment of FIG. 9, the opposite end elevational view being a mirror image thereof;

FIG. 12 is a back plan view of the embodiment of FIG. 9, showing the decorative pattern as seen from the back side of the bandage;

FIG. 13 is a plan view of a fourth embodiment of an adhesive bandage with a decorated absorbent pad showing my new design;

FIG. 14 is a side elevational view of the embodiment of FIG. 13, the opposite side elevational view being a mirror image thereof;

FIG. 15 is an end elevational view of the embodiment of FIG. 13, the opposite end elevational view being a mirror image thereof;

FIG. 16 is a back plan view of the embodiment of FIG. 13, showing the decorative pattern as seen from the back side of the bandage;

FIG. 17 is a plan view of a fifth embodiment of an adhesive bandage with a decorated absorbent pad showing my new design;

FIG. 18 is a side elevational view of the embodiment of FIG. 17, the opposite side elevational view being a mirror image thereof;

FIG. 19 is an end elevational view of the embodiment of FIG. 17, the opposite end elevational view being a mirror image thereof;

FIG. 20 is a back plan view of the embodiment of FIG. 17, showing the decorative pattern as seen from the back side of the bandage;

FIG. 21 is a plan view of a sixth embodiment of an adhesive bandage with a decorated absorbent pad showing my new design;

FIG. 22 is a side elevational view of the embodiment of FIG. 21, the opposite side elevational view being a mirror image thereof;

FIG. 23 is an end elevational view of the embodiment of FIG. 21, the opposite end elevational view being a mirror image thereof;

FIG. 24 is a back plan view of the embodiment of FIG. 21, showing the decorative pattern as seen from the back side of the bandage;

FIG. 25 is a plan view of a seventh embodiment of an adhesive bandage with a decorated absorbent pad showing my new design;

FIG. 26 is a side elevational view of the embodiment of FIG. 25, the opposite side elevational view being a mirror image thereof;

FIG. 27 is an end elevational view of the embodiment of FIG. 25, the opposite end elevational view being a mirror image thereof;

FIG. 28 is a back plan view of the embodiment of FIG. 25, showing the decorative pattern as seen from the back side of the bandage;

FIG. 29 is a plan view of an eighth embodiment of an adhesive bandage with a decorated absorbent pad showing my new design;

FIG. 30 is a side elevational view of the embodiment of FIG. 29, the opposite side elevational view being a mirror image thereof;

FIG. 31 is an end elevational view of the embodiment of FIG. 29, the opposite end elevational view being a mirror image thereof;

FIG. 32 is a back plan view of the embodiment of FIG. 29, showing the decorative pattern as seen from the back side of the bandage;

FIG. 33 is a plan view of a ninth embodiment of an adhesive bandage with a decorated absorbent pad showing my new design;

FIG. 34 is a side elevational view of the embodiment of FIG. 33 the opposite side elevational view being a mirror image thereof;

FIG. 35 is an end elevational view of the embodiment of FIG. 33, the opposite end elevational view being a mirror image thereof;

FIG. 36 is a back plan view of the embodiment of FIG. 33, showing the decorative pattern as seen from the back side of the bandage;

FIG. 37 is a plan view of a tenth embodiment of an adhesive bandage with a decorated absorbent pad showing my new design;

FIG. 38 is a side elevational view of the embodiment of FIG. 37, the opposite side elevational view being a mirror image thereof;

FIG. 39 is an end elevational view of the embodiment of FIG. 37, the opposite end elevational view being a mirror image thereof; and,

FIG. 40 is a back plan view of the embodiment of FIG. 37, showing the decorative pattern as seen from the back side of the bandage.

The dot-dash lines are included for the purpose of illustrating portions of the adhesive bandage backing layer and absorbent pad that form no part of the claimed design.

It will be appreciated that the adhesive backing layer is plain and unornamented in the sense that there are no decorative features on the adhesive backing layer, and that the texture or other visual appearances of the material of the adhesive backing layer is not illustrated and is not considered a part of the claimed invention. Moreover, it will be appreciated that the adhesive backing layer is not explicitly claimed as either opaque or as translucent, and therefore may be either opaque or translucent.
